Filed Aug. 30, 1963, Ser. No. 76,420

Term of patent 14 years

(Cl. D37—1)

FIG. 1.

FIG. 2.

FIG. 3.

The side not shown is identical to the one revealed in FIGURE 2 and the rear elevation is identical to the front elevation illustrated in FIGURE 3. The bottom is plain except for the four legs at the corners.

I claim:

The ornamental design for a rock polishing machine, as shown and described.
